Primary Examiner — Cynthia Ramirez*Assistant Examiner* — Xavier Marti-Santos(74) *Attorney, Agent, or Firm* — VISTA IP LAW GROUP LLP(57) **CLAIM**

The ornamental design for a salon chair, as shown and described.

DESCRIPTION

FIG. 1 is a front perspective view of a salon chair embodying the new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines, including the diamond pattern on the front surface of the salon chair, the headrest, and the zippers shown in FIG. 3, are for the purpose of illustrating portions of the salon chair, and form no part of the claimed design.
